Attorney

UNITED STATES PATENT OFFICE.

CHARLES E. WHALIN, OF SALT LAKE CITY, UTAH, ASSIGNEE, BY DIRECT AND MESNE ASSIGNMENTS, TO WHALIN AUTO LENS & LIGHT CO., A CORPORATION OF UTAH.

LANTERN GLOBE.

Application filed March 21, 1923. Serial No. 626,558.

To all whom it may concern:

Be it known that I, CHARLES E. WHALIN, a citizen of the United States, residing at Salt Lake City, in the county of Salt Lake and State of Utah, have invented certain new and useful Improvements in Lantern Globes, of which the following is a specification.

My invention relates to lanterns, and has for its object to provide a globe for an electric lantern which is made of a plurality of plano-convex lenses integral at their edges with the contiguous lenses and preferably with the convex surfaces meeting in regular curves to give the globe a spherical shape, except on one face where the glass is extended and externally threaded for fastening the globe in the lantern.

These objects I accomplish with the device illustrated in the accompanying drawings in which similar letters and numerals indicate like parts throughout the several views and as described in the specification forming a part of this application and pointed out in the appended claim.

In the drawings in which I have shown a substantial embodiment of my invention, Figure 1 is an elevation of an electric lantern with one of my globes in place thereon. Figure 2 is a side elevation of the globe in detail with some of the plane surfaces shown in dotted lines. Figure 3 is a section of the globe on line 3—3 of Figure 2. Figure 4 is a section on line 4—4 of Figure 2.

I have shown and I use a common form of electric lantern A having a bail B, a battery container C and a base frame D, which base frame is made of small wires to support the lantern and yet obstruct the rays of light as little as may be while they support the lantern and protect the globe from being broken. An electric bulb E is screwed into the bottom of the battery container C and the commonly used switch is mounted in the side of said container C to open and close the electric circuit of said bulb E, as desired. In the bottom of the said battery container I provide an internally threaded

socket within which is screwed the neck of the globe G. The said globe G is made of lens glass and consists of a plurality of plano-convex lenses, the lower one preferably positioned parallel with the base D of the lantern. In the globe shown in the drawings I have illustrated a globe having a cubiform interior, but other shaped interiors, such as a dodecahedral or an octagonal form may be used, thereby increasing the number of lenses and multiplying the focal points. With the cubiform interior I provide five plano-convex lenses, one at the bottom and one on each side, each integral with the contiguous lenses on its periphery. The cubiform interior is open on the upper side and the material is extended as a neck 1 and is externally threaded, as at 2, to provide a means for securing the globe in the lantern A, and around the bulb E. A globe thus constructed will direct the rays from the electric bulb and focus them at five different points, thereby providing a lantern having five bull's eyes without any additional expense as to current and from the one central bulb E. By increasing the number of plane surfaces on the interior of the globe G the number of focal points will be increased, should that be desired, and the number of bull's eyes multiplied.

Having thus described my invention I desire to secure by Letters Patent and claim:

A lantern comprising a frame in which a globe is mounted and an electric light bulb as its source of illumination; said globe fastened in the bottom of said frame and surrounding said electric light bulb in spaced relation thereto, said globe consisting of five plano-convex integral lenses one forming the bottom of said globe and the other four the sides of said globe integrally formed as a sphere except at the side nearest the frame, which side is extended and externally threaded for engagement with said frame.

In testimony whereof I have affixed my signature.

CHARLES E. WHALIN.
